(57) **CLAIM**

The ornamental design for an endplate, as shown and
described.

DESCRIPTION

FIG. 1 is a first perspective view of an ornamental design for
an endplate, according to the invention.

FIG. 2 is a front view of an endplate of FIG. 1.

FIG. 3 is a back view of an endplate of FIG. 1.

FIG. 4 is a left view of an endplate of FIG. 1.

FIG. 5 is a right view of an endplate of FIG. 1.

FIG. 6 is a top view of an endplate of FIG. 1; and,

FIG. 7 is a bottom view of an endplate of FIG. 1.

The broken line shown is included for the purpose of illustration
and forms no part of the claimed design.
